M. GIANINI

CLOSURE FOR CONTAINERS

Filed Oct. 11, 1922

Inventor:
Mario Gianini,
By his Attorney, Geo. F. Miatto

Patented Sept. 11, 1923.

1,467,578

UNITED STATES PATENT OFFICE.

MARIO GIANINI, OF NEW YORK, N. Y.

CLOSURE FOR CONTAINERS.

Application filed October 11, 1922. Serial No. 593,700.

To all whom it may concern:

Be it known that I, MARIO GIANINI, a citizen of the United States, and a resident of the borough of Bronx, county of Bronx, city 5 and State of New York, have invented certain new and useful Improvements in Closures for Containers, of which the following is a specification sufficient to enable those skilled in the art to which the invention app-10 pertains to utilize the same.

While applicable to containers for commercial commodities generally, my improvements are designed more particularly for use in conjunction with the glass or ceramic 15 jars in which various confections are packed for the market, and especially those of the class in which hermetical sealing is a desideratum; and the invention consists primarily and essentially in the use of an in-20 terior supplementary closure disc interposed between the contents of the package and the exterior cover or cap thereof, substantially in the manner and for the reasons herein- after fully set forth.

25 In the accompanying drawings I illustrate a practical embodiment of the essential features of my invention in conjunction with well-known types of containers, although I do not limit myself to the identi-30 cal form and construction of parts shown, since various modifications in minor details and mechanical expedients may be resorted to with like result, and without departing from the spirit and intent of my invention in 35 this respect.

With this understanding,

Fig. 1, represents a central vertical section of a glass jar or container such as used in the packing of hard candies for com-40 mercial purposes;

Fig. 2, is a top view of such a container, without the closure means;

Fig. 3, is a view similar to Fig. 2, with my auxiliary sealing disc in position;

45 Fig. 4, is a top view of said auxiliary sealing disc;

Fig. 5, is a section thereof, taken upon plane of line 5—5, Fig. 4;

Fig. 6, is a central vertical sectional view 50 of the upper portion of a cylindrical container, illustrating a modification in the construction, the closure means being omitted;

Fig. 7, is a top view of the container shown in Fig. 6, also without the closure means;

55 Fig. 8, is a view similar to Fig. 6, illustrating another modification in the construc-

tion of the neck of a container of well known type;

Fig. 9, is a section of the top of a jar, showing still another modification. 60

I herein exemplify my improvements as adapted to glass jars or containers used for the packing of so called hard candies, to which class of goods my improvements are especially applicable, although, as before intimated, I do not limit myself to this nor 65 to any other type of jar, nor to the packing of any particular commodity,—the invention relating to the sealing means exclusively.

Thus, C, represents a container of any 70 well known or desired configuration, formed of glass, ceramic or other material, as may be found most expedient and appropriate for the character of the goods to be packed for the market,—glass jars being preferable 75 as containers for hard candies, confections, and analogous commercial commodities. The outer cover or cap K, is also of secondary importance in that any desired or well known device of this character may be used 80 in conjunction with my inner or auxiliary closure disc A, as for instance a gasket-cover such as shown in Fig. 1; and also applicable to the form of jar shown in Fig. 8, forced 85 into place over the peripheral edge of the jar; or a screw cap may be provided for as in Figs. 6 and 9, of the drawings. In either and any case the function of the exterior cover K, is essentially the same as heretofore known in the art, and forms no part of my 90 present invention, the distinctive feature of which is the aforesaid auxiliary interior closure disc A, in conjunction with means for detachably securing the same within the neck 95 of the jar, substantially as herein set forth. 95

Heretofore, in the packing of hard sugar candies in glass jars, it has been the common practice to fill the neck of each jar with a piece of tissue or waxed paper or other suitable material, crushed (without unnecessary 100 compression) into the form of a stopper or wad W, and interposed between the goods and the inner side of the cover; and the packing is usually done by unskilled labor.

Under ordinary conditions, the most im-105 portant consideration in the packing of hard candies in jars is to accomplish the same in such manner as to insure the maintenance of such goods in perfect condition, as by the hermetical sealing thereof. This 110 can be accomplished by the use of various styles of caps and closures in a manner, and

by means, well known in the art, the most satisfactory method, however, being that of vacuum sealing. In every instance, the wad or stopper W, of crushed waxed paper, or equivalent, is resorted to, because without it, it would be difficult and practically impossible to compactly fill the jar with hard candies up to the level of the cover, owing to their shapes and unwieldly, friable character,—so that the omission of said filler wad or stopper W, would result in the movement of the candies as related to each other in the jar, especially during transportation, the disturbance and shaking about of the component parts of the contents of the jar thus involved tending to break or mar the candies superficially, destroying the initial gloss, and resulting in a dusty appearance, before the goods reach the retailer or customer. The said paper wad or stopper W, obviates this to a great extent, but it often happens that the girl packers, in the haste of production, or through carelessness, will not press the paper stopper W, down into the neck of the jar in a proper manner, and as a result a portion of the paper may be allowed to protrude to such an extent that when the cover is applied, the seal will not be hermetical on account thereof, so that in course of time the inlet of air into the jar will impair the appearance, and cause the deterioration of the candies thus imperfectly packed, rendering the goods unmarketable.

By my invention I obviate this difficulty and danger by my auxiliary sealing disc A, because its use necessitates the proper positioning and compression of the wad W, there below, and precludes the possibility of any portion of said pad interfering with or impairing the perfect and satisfactory closing and sealing of the outer cap or cover K.

My auxiliary closure disc A, is preferably, although not necessarily, seated on an internal annular shoulder c, formed in the mouth or neck of the jar or container C, as illustrated in Figs. 1, 2 and 8, of the drawings, although in lieu of the said annular shoulder c, a plurality of spaced apart sections thereof, or supporting lugs or shoulders c', may obviously be substituted, as indicated particularly in Fig. 6, of the drawings. The sealing shoulder c, or plurality of sealing lugs c', c', may, however, be dispensed with in certain cases if preferred, and my auxiliary closure disc A, may be seated, as it were, directly on the top of the filler or wad W, as indicated in Fig. 9, of the drawings,—the really indispensable parts in this respect, being the plurality of spaced-apart disc-retaining lugs or shoulders c", formed internally on the neck of the jar C, for engagement with the upper peripheral edge of said auxiliary closure disc A,—the latter being formed with correspondingly spaced

apart peripheral notches a, a, adapted to fit over said retaining shoulders c", c", for the purpose of applying or removing the said disc A. That is to say, the disc may be applied to, or removed from, the neck of the jar C, by turning the disc so as to bring said peripheral disc notches a, a, into coincidence with said retaining shoulders c", c"—the disc A, being rotated when thus applied to bring the peripheral edges a', a', thereof between the notches a, a, into engagement with the under sides of said retaining shoulders and thereby locking the disc A, in position, as shown in Figs. 1 and 3 of the drawings.

Any desired plural number of these notches a, a, and retaining shoulders c", c", may be provided for the purposes of thus detachably locking my auxiliary closure disc in position, three being a preferable number in this respect, as shown in the accompanying drawings, as attaining the desired result in a simple and effective manner.

My auxiliary closure disc A, may be made of paraffined card-board, or other fibrous or textile material, or of tin or other sheet metal, or in fact of any composition or material affording the requisite degree of permanence in shape.

In order to facilitate manipulation thereof, I form my auxiliary closure disc A, with finger butments or bearings a", a", which may be grasped between the thumb and index finger nails for the purpose of applying or removing the disc, or turning it axially as related to the retainer shoulders c", c", of the jar.

My auxiliary closure disc A, embodies a double function, in that it not only answers the purpose of a supplementary seal as hereinbefore set forth, but also affords a convenient means of closure after the removal of the outer cap or cover K, which is usually so bent or damaged in effecting the opening of the jar as to be practically useless, as a means of proper closure thereafter. Of course where screw caps are used as a means of external closure, the same are not usually damaged by removal, but nevertheless, even in such cases my auxiliary closure disc affords a convenient means of protecting the contents of the jar in the absence of the outer cover.

What I claim as my invention and desire to secure by Letters Patent is,

1. In closures for containers of the characters designated, a jar formed with a plurality of spaced-apart inturned retaining shoulders in the mouth thereof, and an auxiliary closure disc fitting within the mouth of the jar and formed with a plurality of peripheral notches cooperating with said shoulders, substantially in the manner and for the purpose set forth.

2. In closures for containers of the character designated, a jar formed with a plu-

- rality of spaced-apart inturned retaining shoulders in the mouth thereof, and an auxiliary closure disc fitting within the mouth of the jar and formed with a plurality of peripheral notches cooperating with said shoulders, and with manipulative finger contact shoulders, substantially in the manner and for the purpose set forth.
3. In closures for containers of the character designated, a jar formed with disc-supporting means and a plurality of spaced-apart inturned retaining shoulders in the mouth thereof, and an auxiliary closure disc fitting within the mouth of the jar and formed with a plurality of peripheral notches cooperating with said shoulders, substantially in the manner and for the purpose described.
4. In closures for containers of the character designated, a jar formed with disc-supporting means and a plurality of spaced-apart inturned retaining shoulders in the mouth thereof, and an auxiliary closure disc fitting within the mouth of the jar and formed with a plurality of peripheral notches cooperating with said shoulders, and with manipulative finger contact shoulders,

substantially in the manner and for the purpose described.

5. In closures for containers of the character designated, a jar, the mouth of which is formed with a plurality of spaced-apart inturned retaining shoulders and with a disc-supporting annular shoulder, and an auxiliary closure disc fitting within the mouth of the jar and formed with a plurality of peripheral notches cooperating with said shoulders, substantially in the manner and for the purpose described.

6. In closures for containers of the character designated, a jar, the mouth of which, is formed with a plurality of spaced-apart inturned retaining shoulders and with a disc-supporting annular shoulder, and an auxiliary closure disc fitting within the mouth of the jar and formed with a plurality of peripheral notches, cooperating with said shoulders, and with manipulative finger-contact shoulders, substantially in the manner and for the purpose set forth.

MARIO GIANINI.
